UNITED STATES PATENT OFFICE.

SARAH SHAPIRO, OF WATERBURY, CONNECTICUT.

DESIGN FOR A PILLOW COVER.

Application filed December 10, 1924. Serial No. 11,659. Term of patent 8½ years.

To all whom it may concern:

Be it known that I, SARAH SHAPIRO, a citizen of the United States, residing at Waterbury, in the county of New Haven and State of Connecticut, have invented a new, original, and ornamental Design for Pillow Covers, of which the following is a specification, reference being had to the accompanying drawing, forming part thereof.

The figure is a perspective view of my new pillow cover design.

I claim:

The ornamental design for a pillow cover as shown.

SARAH SHAPIRO.
